UNITED STATES PATENT OFFICE.

HERMAN DAVIS, OF NEW ORLEANS, LOUISIANA.

TRUNK.

SPECIFICATION forming part of Letters Patent No. 787,836, dated April 18, 1905.

Application filed January 3, 1905. Serial No. 239,407.

To all whom it may concern:

Be it known that I, HERMAN DAVIS, a citizen of the United States, residing at New Orleans, in the parish of Orleans and State of Louisiana, have invented new and useful Improvements in Trunks, of which the following is a specification.

My invention pertains to trunks of the wardrobe type, and contemplates the provision of a wardrobe-trunk embodying such a construction that its capacity is materially increased without the necessity of making it complicated, cumbersome, and costly.

The invention will be fully understood from the following description and claims when taken in connection with the accompanying drawings, forming part of this specification, in which—

Figure 1 is a perspective view of the trunk constituting the preferred embodiment of my invention as the same appears when entirely open. Fig. 2 is a longitudinal vertical section of the said trunk with all of its parts in their closed position. Fig. 3 is a view similar to Fig. 1 of a modified construction of trunk, and Fig. 4 is a longitudinal vertical section of the latter trunk as the same appears when closed.

Referring by letter to the said drawings and more particularly to Figs. 1 and 2 thereof, A is the body of my novel trunk. The said body is rectangular in form, has a hinged wall *a* at one end extending throughout the greater part of its height, and also has a transverse partition *b* adjacent to the hinged wall, and cleats *c* on its side walls between the said partition *b* and the hinged wall *a*. In the body is preferably placed a tray B, which rests on cleats *d* of the body and is preferably of such a height that its upper side is flush with the partition *b* for the purpose presently set forth. C is a swinging tray embraced in the trunk. The said swinging tray comprises a main wall *e*, hinged at *f* to the partition-wall *b*, side walls *g*, disposed at right angles to the main wall, a cross-bar *h*, connecting the free edges of the side walls *g* at the outer ends thereof, and a bar *k*, interposed between and connecting the main wall *e* and the bar *h*. The bars *h* and *k* brace or lend strength to the

side walls *g* and are preferable for such reason, and the bar *k* also serves for the convenient connection of garment-hangers. (Not shown.) When in its upright position, the tray C is adapted to rest on the upper edge of the partition *b* and also on the cleats *c*, and when the wall *a* is let down, as shown in Fig. 1, it will be observed that said tray C in connection with the body A will form a convenient wardrobe and one adapted to hold in orderly arrangement a large number of garments. This adaptability of the tray to hold a large number of garments placed one in front of the other is due to the depth of the tray, and in order to provide for the proper accommodation of the tray in the trunk when closed without employing a body A of undue height I so relatively arrange the tray C and the body A that the former projects above the latter when resting in its horizontal position and on the removable tray B, as shown in Fig. 2. D is the top of the trunk. The said top comprises a main portion *l* and flanges *m*, and one of the flanges is hinged to a corresponding side wall of the body A, whereby it will be seen that when the top is let down it will accommodate and entirely inclose the before-mentioned projecting portion of the tray C. A strap, such as *p*, or any other suitable device is preferably employed in connection with the top D to hold the said top against movement beyond the vertical, as shown in Fig. 1. Any means compatible with the purposes of my invention—such, for instance, as the hooks *r* and the complementary eyes *s*—may be provided in the trunk with a view of holding the wall *a* against the side walls of the body A when the trunk is closed.

In the practical use of the embodiment of my invention described the said embodiment is opened by raising the top D to an upright position, unfastening and swinging the wall *a* downwardly until said wall rests on the floor, and swinging the tray C into an upright position. With this done, it will be observed that the tray C, in connection with body A, will form a wardrobe of considerable capacity and one from which garments may be removed with great facility and in which garments may be replaced with equal facility. It will also

be observed that when the tray C is in an upright position the weight of the garments will tend to retain it in such position, and, further, that with the tray C retained in the upright position ready access may be had to the tray B, and the said tray B may, if desired, be removed from and replaced in the body A with facility. To close the trunk, the wall *a* is swung to its upright position and fastened, 10 the tray C is lowered to its horizontal position, and the top D is let down, when the several movable parts will occupy the relative positions shown in Fig. 2.

The modified construction shown in Figs. 3 15 and 4 is generally similar to the embodiment of the invention illustrated in Figs. 1 and 2. The said modified construction, however, differs from that in Fig. 1 in that it lacks the hinged wall *a* and cleats *c* on its body A' and 20 is provided on its tray B' with a supplemental cross-bar *h*'. This cross-bar *h*' is designed to assist in properly holding garments in the tray B' incident to swinging said tray and also when the tray is at rest in its upright and 25 horizontal positions.

In a contemporary application of even date herewith, Serial No. 239,406, I have disclosed a trunk embodying a body and a vertically-swinging tray hinged to the body. The said 30 tray, however, differs from that comprised in the present embodiments of my invention in that it is hinged to one end wall of the body and is open at its inner side.

I have entered into a detailed description 35 of the construction and relative arrangement of the parts included in the present and preferred embodiments of my invention in order to impart a full, clear, and exact understanding of the said embodiments. I do not desire, however, to be understood as confining myself to such specific construction and relative arrangement of parts, as such changes or modifications may be made in practice as fairly fall within the scope of my invention as 45 claimed.

Having described my invention, what I claim, and desire to secure by Letters Patent, is—

1. In a wardrobe-trunk, the combination of 50 a body, a vertically-swinging tray hinged to the body adjacent to one upright end wall thereof and comprising a main wall and side walls; said tray and body being so relatively arranged that when the tray is swung into a 55 horizontal position it will project above the body, and a top hinged to an upright wall of the body other than the end wall mentioned, and comprising a main wall and flanges; said top being arranged when closed to receive the 60 upwardly-projecting portion of the tray.

2. In a wardrobe-trunk, the combination of 65 a body, a swinging tray hinged at one end in the body at an intermediate point in the length of the body and adjacent to one end thereof and comprising a main wall and side walls ex-

tending from the main wall toward the said end of the body; said tray and body being so relatively arranged that when the tray is swung into a horizontal position it will project partly above and partly below the upper 7c edge of the body, and a top hinged to an upright wall of the body other than the end wall mentioned and comprising a main wall and flanges, whereby when said top is closed it is adapted to receive the upwardly-projecting 75 portion of the tray.

3. In a wardrobe-trunk, the combination of a body, a swinging tray hinged to the body and comprising a main wall, side walls, a cross-bar connecting the free edges of the side walls 80 at the outer ends thereof and a bar interposed between the main wall and the cross-bar and adapted to support garment-hangers or the like; said tray and body being so relatively arranged that when the tray is swung into a 85 horizontal position it will project above and below the upper edge of the body, and a top hinged to the body and comprising a main wall and flanges, whereby when said top is closed it is adapted to receive the upwardly-projecting portion of the tray.

4. In a wardrobe-trunk, the combination of a body having a hinged, downwardly-swinging wall at one end, means for retaining said wall in its closed position, a swinging tray 95 hinged at one end in the body at a point adjacent to the hinged end wall and comprising a main wall and side walls extending from the main wall toward the said hinged end wall of the body; said tray and body being so relatively arranged that when the tray is swung into a horizontal position it will project partly above and partly below the upper edge of the body, and a top hinged to an upright wall of the body, other than the first-mentioned wall, 100 and comprising a main wall and flanges, whereby when said top is closed it is adapted to receive the upwardly-projecting portion of the tray.

5. In a wardrobe-trunk, the combination of a body having a transverse partition-wall of a less height than its other upright walls, a swinging tray comprising a main wall hinged at one end to the upper end of said partition-wall and side walls disposed at right angles 115 to the main wall; said side walls being arranged to project upwardly from the main wall and above the upper edges of the body when the tray is in a horizontal position, and a top hinged to the body and comprising a 120 main wall and flanges, whereby when said top is closed it is adapted to receive the upwardly-projecting portion of the tray.

In testimony whereof I have hereunto set my hand in presence of two subscribing witnesses.

HERMAN DAVIS.
